UNITED STATES PATENT OFFICE.

CHAUNCEY B. FORWARD, JR., AND LOUIS D. FORWARD, OF URBANA, OHIO.

AEROPLANE.

1,218,387.

Specification of Letters Patent.

Patented Mar. 6, 1917.

Application filed May 1, 1916. Serial No. 94,582.

To all whom it may concern:

Be it known that we, CHAUNCEY B. FORWARD, Jr., and LOUIS D. FORWARD, citizens of the United States, residing at Urbana, in the county of Champaign and State of Ohio, have invented certain new and useful Improvements in Aeroplanes, of which the following is a specification.

Our invention comprises an aeroplane in which a multiple of planes are used in stepped relation and supported and operated in a particular way to stabilize the machine in flight, and while ascending and descending, all substantially as herein shown and described and more particularly pointed out in the claims.

In the accompanying drawings, Figure 1 is a side view of our improved aeroplane, and Fig. 2 is a front view thereof. Fig. 3 is a plan view of the machine, and Fig. 4 an enlarged cross section and detail of the rack and gear mechanism for operating the movable frame for the hinged planes.

Our improved machine consists of a body 2 adapted to contain the machinery and passengers and having the form of an inverted triangle made of bamboo or tubing sections coupled together and cross-braced and guyed in any suitable way and also covered preferably to provide vertically-inclined surfaces serving as aids in maintaining vertical stability. Body 2 extends lengthwise centrally of the machine and terminates at its opposite ends in a prow 3 and a braced stern 4, the latter carrying a rudder 5. A wheeled alighting gear consisting of two reversely-inclined spring frames 6 carrying wheels 7 forms the under part of body 2, while the superstructure comprises a multiple of planes 8 of equal size, four in all, which are hinged at their front bars 9 to the upper ends of the laterally-inclined struts 9' extending upwardly at spaced intervals from the sides of body 2. The front and rear planes 8 are located on the same level, but the intermediate planes are lower and in stepped relations thereto and to each other, this arrangement tending constantly to maintain the balance of the machine in the air.

These planes are also adapted to be operated jointly to change their angle of incidence in rising or lowering movements or in stabilizing the machine, the controlling means for this purpose involving a verti-

cally-movable frame 10 having separate uprights 11 supporting each plane at its rear end and each upright 11 having a toothed rack 12 at its lower end held in mesh with gear wheels 13 by suitable straps 14 affixed to the top sides of body 2, see Fig. 4. The gear wheels 13 are carried by two shafts 15 extending longitudinally of body 2, said shafts being mounted in suitable brackets 16 at the top sides of the body adjacent each upright, see Fig. 1, and a uniform speed of rotation is given to both shafts 15 by a short transverse shaft 17 having worm gears 18 engaging spiral gears 19 on shafts 15. A hand-wheel 20 serves to rotate shaft 17 and the worm gearing effects self-locking of the parts in the interim of rotation. Moreover, all four planes are controlled and their positions fixed by said worm gear mechanism and frame 10.

The rudder 5 is operated and controlled by cables 21 wound on a shaft 22 having a hand wheel 23, and the propelling power for the machine is obtained by two sets of propellers 24 and 25 driven by two engines 26 and 27 located fore and aft in body 2. The front propellers 24 are located preferably beneath the lateral space between the two front planes, and the rear propellers 25 beneath the space between the two rear planes, and braced outriggers 28 extend at each side of the body to support the propellers apart therefrom and from the running or alighting gear. All the devices and parts commonly utilized to strengthen and operate an aeroplane have not been shown in the drawings, but as these form no part of the invention, their showing would be superfluous.

What we consider new and useful and desire to claim, is:

1. In an aeroplane, a series of planes in tandem and the front and rear planes at the same elevation and the intermediate planes on a lower elevation and in stepped relation rearward, a rigid frame uniting said planes, and gear mechanism for raising and lowering said frame and planes simultaneously.

2. In an aeroplane, a main frame having vertical struts and a plurality of planes hinged thereto, in combination with a movable frame extending longitudinally of the main frame having a pair of uprights connected with the rear of each plane and said uprights having racks thereon, a set of shafts

having pinions engaging said racks and a transverse shaft having worms in geared relations with said shafts.

3. In an aeroplane, a triangular frame having struts in pairs inclined laterally from a given point to V shape and a plane for each pair having a front bar hinged to said struts, in combination with a pair of vertical uprights pivotally connected to each 10 plane and having racks on their lower ends, and means mounted upon said frame to movably support said uprights to change the angle of incidence of said plane comprising

ing two shafts and pinions thereon engaging said racks and a single transverse shaft 15 having a hand wheel to rotate the same and worms thereon operatively engaged with said shafts.

In testimony whereof we affix our signatures in presence of two witnesses.

CHAUNCEY B. FORWARD, JR.
LOUIS D. FORWARD.
